UNITED STATES PATENT OFFICE.

CHARLES H. NORTON, OF WORCESTER, MASSACHUSETTS, ASSIGNOR TO NORTON
GRINDING COMPANY, OF WORCESTER, MASSACHUSETTS, A CORPORATION OF
MASSACHUSETTS.

BELT DRIVE FOR GRINDING-MACHINES.

1,261,156.

Specification of Letters Patent.

Patented Apr. 2, 1918.

Application filed October 18, 1915. Serial No. 56,390.

To all whom it may concern:

Be it known that I, CHARLES H. NORTON, a citizen of the United States, residing at Worcester, in the county of Worcester and 5 State of Massachusetts, have invented a new and useful Belt Drive for Grinding-Machines, of which the following is a specification.

This invention relates to a belt drive for 10 a grinding machine and also to improved devices for preventing access of water to the driving belt.

It is desirable for many reasons that the belt drive of a grinding wheel shaft should 15 be from below rather than overhead. The advantages of the underneath drive include increased safety, cleanliness, and light as well as a marked improvement in general appearance.

20 Under modern conditions a grinding machine of the type herein considered is always provided with means for supplying water to the grinding wheel and the work. In order to prevent this water from reaching 25 the driving belt it has been the practice heretofore to carry the belt rearwardly from the pulley on the grinding wheel shaft in order to avoid contact with the water thrown from the grinding wheel. This construc-

30 tion necessitated the use of two or more guide and take-up pulleys and prevented the use of a straight direct drive from a power shaft in the base of the machine to the grinding wheel shaft.

35 It is the object of my present invention to provide a grinding machine with a direct belt drive from the power shaft to the grinding wheel shaft and also to provide improved devices for protecting the driving 40 belt from water.

With this object in view one important feature of my invention relates to the provision of a trough in the grinding machine base having a reentrant portion providing 45 clearance for the straight run of the driving belt and in the further provision of a guard plate carried by the wheel slide and closing the open upper end of the reentrant portion of the trough in all positions of the wheel 50 slide.

Further features of my invention relate to certain arrangements and combinations of parts which will be hereinafter described

and more particularly pointed out in the appended claims.

A preferred form of my invention is 55 shown in the drawings, in which—

Figure 1 is an end elevation of a grinding machine having a portion cut away to show the construction of the trough and guard 60 plate;

Fig. 2 is a partial end elevation similar to Fig. 1 but showing the wheel slide in extreme forward position;

Fig. 3 is a partial front elevation showing 65 the belt drive for the grinding wheel;

Fig. 4 is a partial sectional plan view taken on the line 4—4 of Fig. 3, and

Fig. 5 is a view similar to Fig. 4 but taken on the line 5—5 of Fig. 3.

Referring to the drawings I have shown 70 my invention as embodied in a grinding machine of a common type. The base 10 of the machine is provided with ways 11 and 12 for supporting and guiding a longitudinally, movable work table 13. The base 10 is also provided with a second set of ways 14 and 15 (Fig. 3) for supporting and guiding a transversely movable wheel slide 16. The grinding wheel W is mounted upon the 80 wheel shaft 17 rotatable in bearings 18 and 19 carried by the wheel slide 16.

A pulley 20 is fixed to the shaft 17 between the bearings 18 and 19 and is connected by a driving belt 21 to a driving 85 pulley 22 mounted upon the power shaft 23. The shaft 23 is supported in bearings 24 and 25 on the base 10 and may be driven by a clutch pulley 26 or in any other convenient manner.

90 A tightener pulley 27 is mounted upon a swinging arm 28 pivoted to swing about the axis of the power shaft 23. The arm 28 is engaged by one end of a coil spring 29 (Fig. 3) fixed to the bearing 25 and is forced yieldingly forward by said spring to bring the pulley 28 into engagement with the belt 21. The pulley 27 thus acts as a tightener for the belt 21 and permits the belt to adjust itself to the different transverse positions of the 100 shaft 17.

A nozzle 30 is supported upon the wheel slide and is connected by a flexible pipe 31 to any suitable source of water supply. The cooling water after leaving the nozzle 30 105 engages the wheel and the work and is then

collected in a trough 32 formed in the base 10. Any suitable provision (not shown) may be made for disposing of the water collected in the trough 32.

5 It will be noted by reference to Figs. 1 and 2 that the driving belt 21 in its straight substantially vertical run from the pulley 20 to the pulley 22 travels downward at the extreme front end of the wheel slide and 10 closely adjacent to the trough 32. In order to fully protect the belt 21 from contact with the cooling water I provide a re-entrant portion 32^a (Figs. 1 and 5) in the trough 32, said portion being of sufficient 15 width and length to provide clearance for the belt 21 in every position thereof.

The upper end of this re-entrant portion, is open and some form of closure is necessary to prevent the entrance of water 20 therein. For this purpose I provide a guard plate 33 fixed to the front end of the wheel slide 16 and having a forwardly projecting portion 33^a sufficient in extent to cover the re-entrant portion 32^a of the trough 32 25 in every position of the slide. The guard plate is also provided with a depending flange 33^b inclosing said re-entrant portion upon three sides thereof and thus effectually preventing access of water to the belt 21. 30 By the constructions above described I secure a direct belt drive from the power shaft 23 to the wheel shaft 17 and I effectually protect the belt from contact with the cooling water in every position of the wheel 35 slide.

Having thus described my invention it will be evident that changes and modifications can be made therein by those skilled in the art without departing from the spirit 40 and scope thereof as set forth in the claims, and I do not wish to be otherwise limited to the details herein disclosed, but what I do claim is:—

1. In a grinding machine, in combination, 45 a base, a work supporting table movable longitudinally of said base, a wheel slide movable transversely on said base, a grinding wheel and shaft mounted on said slide, and a self-contained underneath drive 50 for said grinding wheel, said drive comprising a power shaft mounted in said base substantially beneath said wheel shaft, pulleys on said power shaft and said wheel shaft, a belt directly connecting said pulleys and 55 having a straight clear substantially vertical driving run between said pulleys on the front side thereof, and a tightener pulley

yieldingly engaging said belt on its slack side.

2. In a grinding machine, in combination, 60 a base, a work supporting table movable longitudinally of said base, a wheel slide movable transversely on said base, a grinding wheel and shaft mounted on said slide, a power shaft mounted in said base substantially beneath said wheel shaft, pulleys on 65 said shafts, a belt on said pulleys having a straight clear substantially vertical driving run adjacent the front end of said wheel slide, a tightener pulley yieldingly engaging 70 the slack run of said belt, means to supply water to said grinding wheel, and means to protect the straight run of said belt from said water in every position of the wheel slide. 75

3. In a grinding machine, in combination, 80 a base, a wheel slide movable transversely thereof, a grinding wheel and shaft mounted thereon, a pulley on said shaft, a belt for driving said pulley having a straight substantially vertical run adjacent the front 85 end of said wheel slide, means to supply water to the wheel and work, and means to protect said belt from water, said means comprising a trough in said base adapted to receive said water and having a re-entrant portion to provide clearance for said belt, and a guard plate carried by said wheel slide covering said re-entrant portion and preventing entrance of water to said clearance space. 90

4. In a grinding machine, in combination, 95 a base, a work supporting table movable longitudinally of said base, a wheel slide movable transversely on said base, a grinding wheel and shaft mounted on said slide, a power shaft mounted in said base substantially beneath said wheel shaft, a direct driving connection from said power shaft to 100 said wheel shaft comprising pulleys on said shafts, a belt on said pulleys, and a tightener pulley yieldingly engaging said belt, means to supply water to said grinding wheel, and means to protect said belt from water in every position of the belt, said 105 means comprising a trough in said base having a re-entrant portion providing clearance for said belt and a guard plate mounted on the wheel slide and movable therewith, said plate covering said re-entrant portion and inclosing the same upon three sides thereof to prevent access of water to said belt. 110

CHARLES H. NORTON.
